DROPOUT FUSE CUTOUT

Austin J. Fink and Robert F. Shelton, Bloomington, Ind., assignors to Westinghouse Electric Corporation, East Pittsburgh, Pa., a corporation of Pennsylvania

Filed Feb. 23, 1961, Ser. No. 91,219

5 Claims. (Cl. 200—114)

This invention relates, in general, to electric circuit interrupters, and, more specifically, to dropout fuse cutouts.

This invention is an improvement over the dropout fuse cutout disclosed and claimed in copending application Serial No. 848,596, filed October 26, 1959, by Austin J. Fink, and assigned to the assignee of the present application.

It is an object of this invention to increase the interrupter rating of the dropout fuse cutout in the hereinbefore mentioned copending application.

More specifically, it is an object of this invention to increase the rating of the fuse cutout of the copending application by improving the operating mechanism and contact assembly mechanism.

Still more specifically, it is an object of this invention to increase the rating of the fuse cutout of the copending application by increasing the bursting strength of the fuse holder, by strengthening portions of the operating mechanism to withstand greater reaction due to jet forces on the operating mechanism during circuit interruption, and by utilizing contacts maintaining contact more firmly to resist possible burning of the contact surfaces and to provide relative movement between parts during interruption without overstressing the stationary contacts.

Further objects and advantages will readily become apparent to those skilled in the art upon reading the following specification, taken in conjunction with the drawings, in which:

FIG. 1 illustrates a generally vertical sectional view taken through the enclosed fuse cutout of the present invention, the fuse holder door being shown in side elevation, and the fuse cutout being illustrated in its operative condition for carrying line current therethrough;

FIGS. 2 and 3, respectively, are side elevational and rear elevational views of the improved latch bracket, which is secured to the cutout door;

FIGS. 4 and 5, respectively, illustrate side elevational and rear elevational views of the improved support link or terminal hinge, which forms a part of the door assembly of the cutout;

FIGS. 6 and 7, respectively, illustrate side elevational and rear elevational views, of the assembly of the spring-biased, fuse-link flipper device mounted upon the terminal hinge;

FIGS. 8 and 9, respectively, illustrate front elevational and side elevational views of the mounting bracket for the contact assembly;

FIGS. 10 and 11, respectively, illustrate front elevational and side elevational views of the substantially elongated, box-like support terminal for each contact assembly;

FIGS. 12 and 13, respectively, illustrate top plan and side elevational views of the improved contact for the upper contact assembly of the fuse cutout;

FIGS. 14 and 15, respectively, illustrate top plan and

2

side elevational views of the back-up spring for the upper contact assembly of the fuse cutout;

FIGS. 16 and 17, respectively, illustrate top plan and side elevational views of the improved lower contact assembly;

FIGS. 18 and 19, respectively, illustrate top plan and side elevational views of the back-up spring for the lower contact assembly;

FIG. 20 is a top plan view of the improved latch means for locking the fusible device into the upper contact assembly of the fuse cutout.

Referring to the drawings, and more particularly to FIG. 1 thereof, the reference numeral 1 generally designates an enclosed fuse cutout. It will be noted that generally the fuse cutout 1 includes an insulating housing 2, which may be formed of any desired insulating material, such as porcelain.

The porcelain housing or box 2 comprises a rear wall 3, a top wall 4, and oppositely disposed side walls 5, 6, 20 only the one side 5 being shown. It will be noted, therefore, that the front and bottom of the porcelain box 2 are open. The rear wall 3 is provided with an inwardly extending protuberance 7 forming with an integral flange 8 a transverse baffle intermediate the ends of the insulating casing 2. The protuberance 7, as shown, is provided with a cavity 11 opening to the outer side of rear wall 3 and adapted to receive one end of a mounting bracket 12 for supporting the casing 2, for example, from a cross-arm hanger.

30 As shown in FIG. 1, the mounting bracket 12 may be apertured, as at 15, to provide better securement within a resilient cement 16 contained within the cavity 11 and may be of a type described in the hereinbefore mentioned copending application. The cavity 11 may also be sanded 35 during fabrication of the fuse casing 2 for additional strength of securement.

Within insulating casing 2 there is provided upper and lower contact assemblies 17 and 18, respectively, secured 40 within cavities 21, 22, respectively, provided in the inner surface of rear wall 3 of the casing 2. The upper contact assembly 17 includes a forwardly projecting U-shaped contact strip 23 (FIGS. 12, 13) of any desired conducting material, such, for example, as copper or the like, with a resilient U-shaped backing strip 24, shown more 45 clearly in FIGS. 14 and 15 of the drawings. Preferably, the backing strip 24 is formed from a suitable resilient material, such as Phosphor bronze.

The intermediate portions of each leg of the U-shaped contact 23 converge as at 25, 25 and the end portions 50 flare outwardly of the basic U-shape as at 26, 26 to receive and seat the upper end of a fuse element 33 as herein-after described. The flared portions 26 are canted outwardly and downwardly with respect to a direction parallel to the basic plane of the strip so as to form a seat 55 for the fuse tube perpendicular to the first described seating direction.

The resilient backer 24 includes intermediate converging leg portions 27, 27 for mating with the curved 60 portions 25, 25 of the U-shaped contacts 23, and flared end portions 28, 28 for mating with flared or canted end portions 26, 26 of contacts 23.

The lower contact assembly 18 includes a U-shaped contact strip 31 and a resilient U-shaped backing strip 32, 65 the latter being formed from a resilient metallic material,

such Phosphor bronze. The intermediate portions of the contact legs converge at 34 and the end portions diverge at 35 to form a sloped surface suitable for engaging and stopping the movable contacts to be hereinafter described. The intermediate and outer portions 38 of the contact backer 32 are curved to respectively mate with the intermediate and outer portions 34, 35 of the contact strip 31.

As shown in FIG. 10, the support terminal 38 has a pair of apertures 42 for receiving studs 43 anchoring the stationary contacts 23 and backer 24 to the end of support 38.

The contact and backing strips of both the contact assemblies 17, 18 are mounted in position between one side 37 of the an elongated box-shaped support terminal 38 (FIG. 11) and the upper side 39 (FIG. 9) of an angle-shaped support bracket 40, a pair of rivets 41 being employed for the connection.

It will be observed that contact strip 23 has a downwardly extending end portion 44 (FIG. 13), which is disposed within box-shaped support terminal 38, as more clearly shown in FIG. 1 of the drawings. Lower contact strip 34 (FIG. 17) likewise has a depending portion 45, which is similarly positioned. A pair of terminal screws 46 are threaded into threaded apertures 47 (FIG. 10) of each support terminal 38 and have contacting shoe clamps 48 rotatably secured thereto at the inner ends thereof.

As a result of the foregoing construction the line conductor and also the load conductor, not shown, may be threaded into the side lead openings 49 of casing 2 and forced under pressure by the contacting shoe clamps 48 directly against the curved depending receptive portions 44, 45 of contact strips 23, 31, respectively. As a result, no unnecessary joints are provided in the current path extending through the fuse cutout 1.

It will be noted that the angled support brackets 40 have an angled portion 50, which is cemented into the cavities 21, 22 of the casing 2. Any suitable cement, such as high-strength mineral lead cement 51 may be employed.

With reference to FIG. 1, it will be noted that the porcelain fuse housing 2 is provided with threaded metallic pivot pins 53 extending through opposite sides 5, 6 of the housing 2 and retained by cooperating insulating nuts (not shown). The pins 53, only one of which is shown, form inwardly extending trunnions to removably pivotally support a fuse-holder door, generally designated by the reference numeral 57.

Preferably the fuse-holder door 57 is formed of a suitable insulating material, such, for example, as porcelain, a synthetic resin, or the like. The molded door 57 is provided with an apertured handle 58, which may be manipulated by a switch stick at a distance, or by hand for the lower voltages. The opening 59 in the handle 58 may be grasped by the hand of the lineman, but preferably, for reasons of safety, switch stick operation is desirable with the prong of the switch stick inserted within the opening 59 to effect closing and opening rotative motion of the fuse-holder door 57 about the pivot pins 53, as hereinafter more fully described.

Fuse-holder door 57 comprises a door panel 60 having a rearwardly extending integral, apertured mounting projection 61. In addition, door 57 has an intermediately disposed recess 63 for the accommodation of a sponge rubber, washer-shape barrier member 64, and rivets 65 molded with the door. Also fuse-holder door 57 has a transverse integral flange 66 with an arcuate cutout portion, not shown, for accommodating a tubular fuse holder, generally designated by the reference numeral 68. The lower portion of the molded door 57 is provided with a pair of trunnion-receiving flared notched 71 for receiving the pivot pin 53 on casing 2. The top of the door 57 is provided with a top, inwardly extending flange portion 73.

The tubular fuse holder 68 comprises a top knurled contact cap 74, which is threaded into a fuse ferrule 75, the

latter, in turn, being threaded upon the upper threaded end of a fuse tube 76 and fixedly cemented thereto.

It will be noted that the contact cap nut 74 of fusible device 33 is tapered from the base upwardly toward the top to fit in mating relation with the previously described flared portion 26 of contacts 23. In addition, the cap has a cylindrical recess 77, which is engaged by the latching portion 67 of spring latch 72 (FIG. 20). The spring latch 72 has a coiled base portion terminating in ears 52 for attaching the latch to the support 38 by way of studs 43. The coiled wire spring is better able to absorb the greater reaction due to jet forces during interruption. The coiled spring can better absorb deflection due to these forces than can the flat spring of the copending application.

The mounting aperture 78 of mounting projection 61 has a shoulder portion 81, which limits the downward movement of fuse ferrule 75 when tubular fuse holder 68 is inserted into mounting aperture 78.

As well known by those skilled in the art, a button-type fuse-link assembly, generally designated by the reference numeral 82, is inserted into the top of tubular fuse holder 68 following removal of knurled contact cap 74. The buttonhead of the link assembly is clamped between the bottom of the contact cap 74 and a threaded plug, not shown, threaded interiorly within fuse ferrule 75. The fuse link may be of the type described in United States Patent 2,343,723, issued March 7, 1944, to James M. Wallace and assigned to the same assignee as the present application.

The lower cable or tail 83 of the fuse-link assembly 82 extends through the lower open end of the bore provided within fuse tube 76 and is clamped between a freely rotatable washer 84 of a terminal clamp 85 and the knurled side 86 (FIG. 5) of a pivotally mounted support link, or door hinge 87, shown more clearly in FIGS. 4 and 5 of the drawings. In the intact, or unblown condition of the fuse link 82, as illustrated in FIG. 1, a toggle means 88 is maintained in its set or unbroken position. However, when fuse link 82 fuses upon overload or fault-current conditions, the cable 83 is released, and the toggle means 88 breaks, or collapses, to permit lowering and outward movement of the fuse-holder door 57 and consequent unlatching of contact cap 74 from latching spring 72. The entire fuse-holder door 57 then drops downwardly to the dropout indicating position shown by dot-dash lines in FIG. 1.

Preferably, the fuse tube 76 is composite in construction having an inner gas-evolving liner of fiber, or like material, and an outer surrounding casing of insulating material preferably glass reinforced epoxy. By using a strong outer layer, greater bursting strength is achieved and a thinner outer wall is permitted, thus allowing a thicker layer of fiber. The thicker fiber provides a greater ability to withstand erosion due to arcing. The evolution of the gas from the fiber liner during the drawing of the arc within the fuse-tube bore will assist in arc extinction, the evolved gas being expelled downwardly through the lower open end of the fuse tube 76 with expulsive action. This expulsive action will, of course, assist in the ejection of the lower remnant of the fuse link out of the fuse tube.

With reference to FIGS. 2 and 3, it will be noted that the rivets 65, molded with the door 57, are employed to secure fixedly in place a latch bracket, or catch 93. The rivets 65 extend through holes 94 of latch bracket 93 and have their inner ends swaged, or peened over to rigidly mount the latch bracket 93 on the door 57. Preferably, a resilient rubber pad 95 of generally rectangular configuration is disposed between the inner side of the door panel 60 at the bottom of a recess 96, and the bight portion 97 of latch bracket 93 for minimizing shock imposed upon the molded door 57 during operation of the cutout. The pad 95 is, of course, provided with apertures to accommodate the pair of rivets 65.

As shown in FIGS. 2 and 3, the legs 98 of latch bracket 93 have three threaded holes 99 provided in the sides 98 of the latch bracket 93. The upper two holes 99 receive the inner ends of pivot screws 102 (FIG. 1), the shank portions of which pass with clearance through pivot holes 103 (FIG. 4) of supporting link 87. The inner extremities of the two pivot screws 102 extend into bored openings, or recesses provided in the side walls of fuse tube 76. These recesses, not shown, do not, however, extend to the inner surface of the bore extending through fuse tube 76. Thus, the inner ends of the pivot screws 102 serve to fixedly attach the fuse holder 68, including the fuse tube 76, to the door 57. By unscrewing the pivot screws 102, however, the supporting link 87 may readily be removed from the latch bracket 93, or door 57, and the freed fuse tube 76 may be removed from door 57 by upward withdrawal movement through mounting aperture 78 of projection 61. When desired, a new fuse tube 76 may be substituted in this manner for an old fuse tube 76. It is to be noted that the latch bracket 93 has been provided with considerable mass and increased strength by the addition of integral connecting member 101 connecting the legs 98 and the bight portion 97. This structure provides strength to resist the greater reaction forces encountered at the higher interrupter ratings.

The toggle means 88 comprises the fuse holder 68 as one leg of the toggle, and the supporting link 87 as the other leg of the toggle. As shown in FIGS. 1 and 4, the supporting link 87 has provided adjacent the lower end thereof a slot 104 opening to one edge of the link and having a reentrant portion 105 at the inner end thereof for receiving the pivot pins 53 supported upon the side walls 5 and 6 of the casing 2. By the provision of such a slot 104 in supporting link 87, it will be apparent that the link 87 may be readily attached and detached with respect to supporting pivots 53 by movement of the link 87 to cause entrance or exit of supporting pins 53 into slots 104. In the position of the parts shown in FIG. 1 of the drawings, it will be noted that slot 104 in the supporting link 87 lines up with the notches 71 provided in opposite side edges of door panel 60 to permit the link 87, when assembled with the fuse holder 68 and door 57, to be engaged or disengaged with pivot pins 53. The notches 71 in the door panel 60 are, as shown, flared outwardly to facilitate easy entrance of pivot pins 53 into the notches 71 and slots 104 in the supporting link 87.

The lower threaded hole 99, as shown in FIG. 2, accommodates a converting screw 106, which passes with clearance through hole 107 (FIG. 4) of link 87, and thereby adapts the fuse cutout 1 for non-dropout operation. Removal of this converting screw 106, which is mounted in place at the factory, provides dropout operation, since the toggle means 88 is then free to collapse. If the converting screw 106 is maintained in position, as supplied from the factory, the supporting link 87 is rigid with latch bracket 93 and door 57, and the toggle means 88 is rendered inoperable.

With reference to FIGS. 6 and 7 of the drawings, it will be noted that a spring latch, generally designated by the reference numeral 108, is mounted at the lower end of the supporting link 87. This spring latch 108, mounted upon the door-hinge assembly, permits only a correct and controlled force upon the fuse link and aids the fuse cutout 1 in clearing faults. It also serves as a fuse-link flipper, indicating a blown fuse when the fuse cutout 1 is adjusted for non-dropout operation.

The spring latch 108, as shown in FIGS. 6 and 7, includes an elongated metallic sleeve 109 threaded upon the bight portion of a biasing spring 110 comprising two torsion-spring sections 111. The ends 112 of the torsion springs 111 bear upon the under side of the bight portion 86 of supporting link 87. The elongated metallic sleeve 109 is free to roll about the bight portion of the biasing spring means 110.

As shown in FIG. 1, the spring-latch sleeve 109 not only exerts the proper pressure upon the fuse-link assembly 82, but also the metallic sleeve 109 latches behind the depending legs 98 of latch bracket 93 preventing breaking, or collapse of the toggle means 88 until after the fuse link has blown and permitted downward releasing movement of the latching sleeve 109.

With reference to FIG. 4, it will be noted that supporting link 87 has a contacting portion 116 with an arcuate cutout portion 117 for accommodating the fuse tube 76 in the closed-circuit position of the device, as shown in FIG. 1. The contacting portion 116 has flared ends 114 for mating engagement with portions 35 of the lower contact strip 34 of lower contact assembly 18 with a wiping and pressural engagement. The upper contact cap nut 74 likewise engages the contact plate legs 26, 26 with pressural engagement. Thus, adequate contact pressure is provided in the latched closed position of the fusible device 1. This contact pressure tends to cause breaking or collapse of the toggle means 88, which is resisted by the fuse-link assembly maintaining the spring latch in its locking position, as shown in FIG. 1. The use of the U-shaped contacts rather than the flat spring contacts of the copending application provides firmer contact during passage of current which provides magnetic flux holding the contacts together to minimize burning, and, further, the contacts as shown permit an upward motion of the door 57 during interruption without overstressing the stationary contacts. The contact pressure provided between the resilient U-shaped lower contacts 31 and the movable contacts 116 on support link 87 in a direction perpendicular to the fuse tube serves to provide a force urging the fuse tube 68 and support link 87 outwardly of the box 2 to assist in collapsing the previously described toggle mechanism when the fuse link 83 fuses. In the upper contacts, 23, the canted portions 26, 26 permit the fuse tube 68 and contact 74 to drop downwardly during the toggle breaking operation.

Referring to FIG. 6, it will be noted that a threaded bushing 118 is brazed to the back side of supporting link 87. The threaded bushing 118 threadedly receives the threaded shank portion of a terminal stud 119 having an integrally formed outer wing nut 120. The stud 119 and wing nut 120 are formed from the same stock, the threads being rolled upon the stock following positioning of the loose washer 84 thereon. The threads have an outer diameter greater than that of the hole through the washer so the washer 84 is held captive. Also, the inner extremity of the terminal stud 119 is upset to render the terminal clamp 85 captive upon the supporting link 87. The loose washer 84 prevents capstan action being exerted upon the fuse-link cable 83 to prevent thereby the imposition of undue stress upon the relatively weak fuse-link assembly 82.

When the line conditions are such as to permit excessive current to flow through the cutout 1 by way of contact assemblies 17, 18 and fuse-link assembly 82, this excessive current will cause fusing of the fusible element disposed within fuse tube 76 and associated with fuse-link assembly 82. The fusing of the fusible element will release the spring-biased latching device 108 causing it to rotate in a counter-clockwise direction about its pivot axis 121. The torsion springs 110, encircling the sleeve 122, quickly force latching sleeve 109 to effect withdrawal of the lower remnant of fuse-link assembly 82 downwardly out of the lower open end of the fuse tube 76. Arc lengthening is thereby augmented, and an indication of a blown fuse condition is obtained. Simultaneously with the withdrawing motion of the fuse-link flipper 108, there occurs unlatching of the cutout toggle mechanism 88. Preferably, arc extinction occurs within fuse tube 76 prior to breaking or collapse of toggle means 88 to prevent any arcing at the contacts. The force exerted by the lower back-up spring 32 acts to break the toggle means 88 and effect counterclockwise rotation of support-

ing link 87 about its pivot axis 53, thus effecting outward and dropping movement of the fuse holder door 57 upon collapse of the toggle means 83. This will release the latching means 67 at the top contact assembly and allow the tapered contact 74 to drop away from the canted contact 23. The fuse holder door 57 will swing in a counterclockwise direction about the pivot pins 53 to the dot-dash open position of FIG. 3.

The lineman will, of course, notice the dropout position of the door, or if non-dropout operation is in effect, indication of the blown condition of the fuse device 33 will be had by the lowered flipper device 103, which serves as a semaphore. If dropout operation is in effect, the lineman will insert a prong of his switch stick within operating eye 124 (FIG. 5) provided in link 87 and remove the fuse holder door 57 from the pivot pins 53. If non-dropout operation is in effect, the lineman must first open the door 57 forcibly by pulling on the prong of the switch stick inserted within door opening 59.

While there has been shown and described a particular embodiment of the invention, it will be obvious to those skilled in the art that changes and modifications may be made without departing from the invention, and that it is intended by the appended claims to cover all such changes and modifications as fall within the true spirit and scope of the invention.

We claim as our invention:

1. A dropout fuse cutout, comprising: an insulating housing having pivot means disposed thereon, spaced upper and lower line contacts mounted on said housing, the upper one of said contacts comprising a pair of resilient spaced opposing finger means extending in a first direction laterally of a direction through said line contacts and each having an inner surface diverging with respect to the other in a direction toward the other line contact; a fuse holder having a contact at its upper end; means including a collapsible linkage pivotally mounted on said pivot means and connected to said fuse holder; fuse link means connecting said fuse holder contact to the lower one of said line contacts and releasably holding said linkage in a non-collapsed position; said linkage being actuatable to pivot said fuse holder contact in a direction opposite to said first direction into engagement with and between said diverging portions of said finger means; latch means engageable with the top of said fuse holder contact to provide a force substantially axially of said fuse holder to releasably maintain the fuse holder contact in engagement with and between said finger means; said linkage being collapsible upon fusing of the fuse link to effect movement of said fuse holder in the direction of said inner surface divergence to effect disengagement of the fuse holder contact from the finger portions of the line contact and the latch means.

2. A dropout fuse cutout, comprising: an insulating housing having pivot means disposed thereon, spaced upper and lower line contacts mounted on said housing, the upper one of said contacts comprising a pair of resilient spaced opposing finger means extending in a first direction laterally of a direction through said line contacts and each having an inner surface diverging with respect to the other in a direction toward the lower line contact; a fuse holder having a contact at its upper end; means including a collapsible linkage pivotally mounted on said pivot means and connected to said fuse holder; fuse link means connecting said fuse holder contact to the lower one of said line contacts and releasably holding said linkage in a non-collapsed position; said linkage being actuatable to pivot said fuse holder contact in a direction opposite to said first direction into engagement with and between said diverging surfaces of said finger means; a spring latch releasably engaging the top of the fuse holder contact to retain the fuse holder contact in engagement with and between said fingers; said linkage being collapsible upon fusing of the fuse link to effect movement of said fuse holder in the direction of said inner

surface divergence to effect disengagement of the fuse holder contact from the finger portions of the line contact and said latch.

3. A dropout fuse cutout, comprising: an insulating housing having pivot means disposed thereon, spaced upper and lower line contacts mounted on said housing, the upper one of said contacts comprising a pair of resilient spaced opposing finger means extending in a direction substantially perpendicular to an imaginary line connecting the contacts and each finger having a surface diverging downwardly; a fuse holder having a contact at its upper end; means including a collapsible linkage pivotally mounted on said pivot means and connected to said fuse holder; fuse link means connecting said fuse holder contact to the lower one of said line contacts and releasably holding said linkage in a non-collapsed position; said linkage being actuatable to pivot said fuse holder contact in a non-axial direction into engagement with and between said diverging portions of said finger means; said fuse holder contact being tapered in a direction axially of the fuse holder at the locus of engagement with said fingers to provide quick disengagement when the linkage collapses; latch means engageable with the top of said fuse holder contact to provide a force substantially axially of said fuse holder to releasably maintain the fuse holder contact in engagement with and between said fingers; said linkage being collapsible upon fusing of the fuse link to effect movement of said fuse holder to effect disengagement of the fuse holder contact from the finger portions of the line contact and the latch means.

4. A dropout fuse cutout, comprising: an insulating housing having pivot means disposed thereon, spaced upper and lower line contacts mounted on said housing, the upper one of said contacts comprising a pair of resilient spaced opposing finger means extending in a first direction laterally of a direction through said line contacts and each having an inner surface diverging with respect to the other in a direction toward the other line contact; a fuse holder having a contact at its upper end; means including a collapsible linkage pivotally mounted on said pivot means and connected to said fuse holder; fuse link means connecting said fuse holder contact to the lower one of said line contacts and releasably holding said linkage in a non-collapsed position, said linkage being actuatable to pivot said fuse holder contact in a direction opposite to said first direction into engagement with and between said diverging portions of said finger means; said contact having a tapered surface engaging the said inner surface of each finger when the fuse holder contact is between the fingers, latch means engageable with the top of said fuse holder contact to provide a force substantially axially of said fuse holder to releasably maintain the fuse holder contact in engagement with and between said fingers; said linkage being collapsible upon fusing of the fuse link to effect movement of said fuse holder in the direction of said inner surface divergence to effect disengagement of the fuse holder contact from the finger portions of the line contact and the latch means.

5. A dropout fuse cutout, comprising: an insulating housing having pivot means disposed thereon, spaced upper and lower line contacts mounted on said housing, each of said contacts comprising a pair of resilient spaced opposing finger means extending in a first direction laterally of a direction through said line contacts, each finger having an end portion diverging with respect to the other finger of the corresponding pair, each finger of the upper contact having an inner surface diverging with respect to the other in a direction toward the lower line contact; a fuse holder having a contact at its upper end; means including a collapsible linkage pivotally mounted on said pivot means and connected to said fuse holder; fuse link means connecting said fuse holder contact to the lower one of said line contacts and releasably holding said linkage in a non-collapsed position, said linkage being actuatable to pivot said fuse holder contact in a direction

direction opposite to said first direction into engagement with and between said diverging portions of said finger means; contact means on the linkage resiliently engageable with the finger portions of the lower of said line contacts when the linkage is in the non-collapsed condition and when the fuse holder is engaged with said one line contact; said another resilient line contact providing a force against said linkage carried contacts tending to assist collapse of said linkage when the linkage is released; latch means engageable with the top of said fuse holder contact to provide a force substantially axially of said fuse holder to releasably maintain the fuse holder contact in engagement with and between said fingers; said linkage being collapsible upon fusing of the fuse link

to effect movement of said fuse holder in the direction of said inner surface divergence to effect disengagement of the fuse holder contact with the finger portions of the line contact and the latch means.
